UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

PRINTING-PRESS.

1,121,159.

Specification of Letters Patent. Patented Dec. 15, 1914.

Application filed July 11, 1914. Serial No. 850,433.

To all whom it may concern:

Be it known that I, HENRY F. BECHMAN, a citizen of the United States, residing at Battle Creek, in the county of Calhoun and 5 State of Michigan, have invented certain new and useful Improvements in Printing-Presses; and I hereby declare that the following is a full, clear, and exact description thereof, reference being had to the accompanying drawings, which form part of this 10 specification.

This invention is a novel improvement in flat-bed type-printing web-perfected printing presses of the well known type in which 15 impressions are taken upon a web from flat forms of type lying upon flat beds by means of cylinders which are reciprocated back and forth over the type. This construction of press is illustrated particularly by the 20 well known "Duplex" and was first disclosed in patent to Cox No. 478,503, dated July 5, 1892.

The object of the present invention is to greatly increase the practical speed of operation of such presses without complicating their parts and thus to enlarge their field of usefulness and enable them to be used in many places where rotary printing presses are now required.

25 The invention will be hereinafter explained in detail and summarized in the claims.

The accompanying drawing represents a partial side elevation and part section of a 35 "Duplex" flat-bed web-perfected press, and I will explain the invention with reference thereto, it being understood that its application is not limited to the particular constructions shown, but that it is a principle 40 applicable to other presses of the same general operative character.

In the drawing 1, 1^a represent superposed type beds mounted in a suitable main frame and 45 slideable cross-heads 2 are mounted to reciprocate back and forth on guide-ways 3 on the frame adjacent the upper bed; said cross-heads being reciprocated by means of pitmen 2^a attached to crank wheels (not shown) in the usual manner.

50 Coöoperating with the type beds 1, 1^a are impression cylinders 4, 4^a which are journaled in the cross-heads 2 as usual; and in these cross-heads are also mounted inking rollers and web guiding rollers in the usual 55 manner. The web W is directed from the

feeding devices (not shown) successively between the cylinders and beds as indicated in the drawings, and thence to the delivery devices (not shown). These parts of the press are well known, and may be constructed and operated substantially as in the well known Duplex press, and as described in the said Cox patent, and therefore further detailed description thereof is unnecessary.

60 In the present known most efficient form of this press the practical speed is from 4500 to 5000 perfected impressions (or newspapers) per hour, according to the size of the press. The first limitation upon the speed of such presses was the inability to shift the web with sufficient rapidity during the short intervals between successive impressions; but this difficulty was successfully overcome; but a heretofore insuperable limitation upon the speed of such presses has 65 been the necessarily great weight of the reciprocating parts, (i. e. the cylinder, cross-heads and pitmen) which in a Duplex press adapted to print an eight-page newspaper is 70 about 3000 pounds, and all this weight had to be reciprocated back and forth over the beds at the rate of 5000 strokes per hour, when the press was run at a speed of 5000 impressions per hour, and it has heretofore 75 been found practically impossible to obtain 80 a higher speed on account of the strains upon the working parts and the vibration caused by the rapid movement and reversals of such a large mass of metal at a speed in 85 excess of 5000 impressions per hour. Because of the low speed of such flat-bed presses, as compared with rotary presses, the field for such flat-bed web-printing presses 90 has been limited to newspapers having a very small circulation; and publishers of 95 newspapers having a larger circulation have been compelled to buy and use expensive stereotype rotary presses in order to get out their papers in time. These facts have been 100 known for years, and many inventions designed to enhance the speed of the Duplex flat-bed press have been made and patented by myself and others during the last twenty 105 years, but, as stated the utmost speed that it has been heretofore possible to obtain in the best of these presses has been about 5000 eight-page papers per hour.

110 My present invention however will greatly increase the speed of such flat-bed presses

and will enable a press like that which has heretofore been capable of printing only about 5000 eight-page papers per hour to print upward of 7500 eight-page papers per hour; and this desirable novel and highly useful result I have accomplished by making the reciprocating parts, such as the cylinders, the cross-heads by which they are operated, and the pitmen by which 10 the cross-heads are connected to the crank wheels, out of what I term aluminum-alloy, (which preferably consists of aluminum, zinc, copper, iron and silica,) and which alloy has a breaking 15 strain approximately equal to that of cast-iron, is about 40% lighter than cast-iron, and is so rigid that it can be successfully used in place of iron or steel for the parts mentioned.

20 The difference in weight of the reciprocating parts of two presses of similar size, one having such parts made in the usual manner of iron and steel, and the other having such parts made of such aluminum-alloy, is about 1100 pounds; or in round numbers the parts made of aluminum-alloy weigh only about 1800 pounds as against 2900 pounds when made as heretofore of iron or ordinary metal. This great reduction 25 in weight is of the utmost practical benefit, for these reciprocating parts have to be started, moved over the type bed and stopped for each printing operation, or newspaper printed on such press.

30 In the old machines the reciprocating parts weighing approximately 2900 pounds were reciprocated over the beds, and were traveled about 38 inches and stopped on each stroke and must make eighty strokes a minute to enable the press to produce about 5000 newspapers an hour; and the vibrations and shocks incident to such movements of this weight rendered higher speeds impractical. But when these parts are made of 35 aluminum-alloy, as described, the weight is reduced 1100 pounds and consequently being so much lighter they can be speeded up to about 120 strokes per minute, and thus produce about 7500 newspapers per hour, with 40 no greater strain upon the parts and no more shock or vibration than occurs in the old machines operated at 80 strokes per minute. By using such aluminum-alloy for the moving parts as aforesaid; the speed of

the press has been actually increased about 55 50%, and such increase in speed proportionately increases the usefulness of such press, and greatly enlarges the field therefor as it enables such presses to be employed 60 for printing newspapers which have hitherto required rotary stereotype presses. The great practical value and utility of the invention will be best appreciated by those skilled in the art who are familiar with the many unsuccessful efforts to increase the 65 speed of such presses, and the great and urgent demand of the trade therefor; and by newspaper publishers who will be thereby saved the necessity of procuring and using expensive rotary presses and stereotyping apparatus, and whose circulations while requiring a press of greater capacity than that of the heretofore known Duplex flat-bed presses will not justify the outlay 70 and expense incident to the purchase and 75 upkeep of a rotary stereotype newspaper printing press.

What I claim is:

1. In a flat-bed web-perfected press, the combination of flat type beds, reciprocating 80 cross-heads, cylinders coöperating with the beds and journaled in said cross-heads, and means for reciprocating the cross-heads, said cylinders being made of aluminum-alloy, as and for the purpose specified. 85

2. In a flat-bed web-perfected press, the combination of flat type beds, reciprocating cross-heads, cylinders coöperating with the beds and journaled in said cross-heads, and means for reciprocating the cross-heads; 90 said cylinders and cross-heads being made of aluminum-alloy, as and for the purpose specified.

3. In a flat-bed web-perfected press, the combination of flat type beds, reciprocating 95 cross-heads, cylinders coöperating with the beds and journaled in said cross-heads, and pitmen for reciprocating the cross-heads; said cylinders, cross-heads and pitmen being made of aluminum-alloy, as and for 100 the purpose specified.

In testimony that I claim the foregoing as my own, I affix my signature in presence of two witnesses.

HENRY F. BECHMAN.
